CARBURETOR METERING CONTROL

James L. Edelen, St. Louis, Mo., assignor to
 Carter Carburetor Corporation, St. Louis, Mo.,
 a corporation of Delaware

Application March 14, 1941, Serial No. 383,293

7 Claims. (Cl. 261—51)

This invention relates to carburetors for internal combustion engines of the automotive type and consists particularly in novel mechanism for providing proper metering of the liquid fuel supply adaptable to a universal type of carburetor and adjustable to conform with the requirements of different engines.

In the well known Carter carburetor, the liquid fuel supplied to the main nozzle is metered through a main metering orifice located at the bottom of the carburetor constant level chamber. A stepped or tapered metering pin cooperates with the metering orifice to vary the effective size of the metering orifice and thus control the richness of the mixture supplied by the carburetor in accordance with the power demand upon the engine. Such a metering arrangement is called an economizer or step-up device. The power demand, in some cases, varies directly with the degree of opening of the carburetor throttle and, accordingly, the economizer may be controlled with the throttle valve by a direct connection thereto. In other cases, it is desirable to provide for variation of the position of the economizer in accordance with suction in the engine intake manifold and more or less independently of the throttle position. For instance, the Chevrolet engine operates very satisfactorily with a carburetor having a so-called manual metering pin, that is, a metering pin which is directly connected to the throttle. On the other hand, the Plymouth engine operates better with a carburetor having a metering pin or needle controlled by suction. Obviously, a carburetor, to operate most satisfactorily with a particular engine, should have either a manual or a suction controlled economizer as determined by the characteristics of the particular engine.

The use of the carburetor with a governor of the flow restricting type alters the metering requirements, particularly in that the economizer should assume a lean position in accordance with the manifold suction as soon as the engine reaches the governed speed, but irrespective of the throttle position, since the drivers of governed vehicles usually hold the throttle valve farther open than is necessary and rely on the governor to limit the speed.

In the Carter carburetor, the metering pin is controlled through the intermediary of the accelerating pump leverage mounted on the fuel bowl cover. The pump piston is operated by a connection to the throttle valve, but frequently, a yielding throttle connection is provided, conve-

niently by means of a split or two-part leverage, the parts of which are resiliently held in their normal functioning position. The present invention contemplates the use of a spring connected to one of the pump leverage parts and which may be attached to the metering pin mechanism to affect the suction control thereof. Obviously, this spring affects the effective resilience of the pump operating connection.

- 10 Accordingly, it is an object of the present invention to provide an automobile carburetor having simply adjustable means to accommodate the carburetor to varied engine and governor requirements, as mentioned above.
- 15 A more specific object is to provide a carburetor in which the metering device may be readily converted from a full manual control to partial manual-partial suction control or to full suction control.
- 20 Still another object is to provide spring means functioning in association with the metering mechanism and the pump leverage for selectively rendering the suction control of the metering mechanism inoperative, partially operative, or
- 25 fully operative without, at the same time, substantially affecting the resilience of the pump-throttle connection.

These objects and other more detailed objects hereafter appearing are attained substantially by the carburetor structure illustrated in the accompanying drawing in which

Fig. 1 is a side view and vertical section showing various parts of the carburetor embodying the invention.

Fig. 2 is a detail side view and section showing a portion of the structure in Fig. 1 but with the manual control of the metering pin eliminated.

Fig. 3 is a view similar to Fig. 2 but showing the parts in a position to attain partial manual and partial suction control of the metering mechanism.

Fig. 4 is a detail view showing the pump leverage stressed.

Fig. 5 is a detail section taken on line 55 of Fig. 1.

The carburetor shown is of the Carter down-draft type including a mixture conduit or barrel including air inlet portion 6 and outlet portion 7 flanged as at 8 for attachment to the usual intake manifold (not shown). A throttle valve 9 is pivotally mounted in the outlet portion on shaft 10 to which is rigidly attached an arm 11.

Located at one side of the mixture conduit is a constant level chamber or bowl 12 within which fuel is maintained at a constant level by the

usual float and needle valve mechanism (not shown). Located in the lower portion of the bowl is a metering orifice member 13 having communication with a cross passage 14 which, in turn, communicates with the main nozzle of the carburetor mounted in an inclined passage, the lower portion of which is indicated at 15. Idling fuel is supplied through a metering tube 16 and suitable passages connected to the usual idling port adjacent the edge of the throttle valve when closed.

At one side of the float bowl there is provided a cylinder 17 which is ported at atmosphere in its upper portion, as at 18 and which, at its lower portion, is connected by means of a passage 19 with the outlet portion of the carburetor mixture conduit posterior to throttle 9. Slidable in cylinder 17 is a piston 20 normally urged upwardly by a coiled spring 21. An L-shaped rod 25 is attached to the upper portion of piston 20 by a pin 26. A metering pin 27 is attached to the upper portion of rod 25 by means of a pin 28 and has a stepped, lower portion, as shown, which extends through metering orifice member 13 for controlling the effective size thereof.

Located in another portion of the float bowl is a second cylinder 29 in which is slidably received a piston 30 normally urged upwardly by a coiled spring 31. A piston rod 32 is attached to the piston and, at its upper end, is connected by means of an operating link 33 to a lever 34 rotatable on a shaft 35 mounted above bowl cover 36. A second lever 37 is also rotatably mounted on shaft 35 and extends oppositely to lever 34, the outer end of lever 37 being connected by a link 43 to throttle arm 11. Levers 34 and 37 are provided, respectively, with ears 41 and 42 normally maintained in abutting relationship by a spring 43 tensioned between a lug 44 on lever 34 and a lug 45 on lever 37. The two-part leverage mechanism, connector rod 42, and arm 11 constitute a resilient operating connection between pump piston 30 and the throttle valve so that when the throttle valve is opened, the pump piston is depressed in cylinder 29 for supplying a "pick-up" charge of fuel into the mixture conduit. Spring 31 beneath the pump piston is weaker than tension spring 42 and merely serves to keep slack out of the pump operating linkage. The pump is provided with the usual intake check 46 in passage 47 communicating with the float bowl, and an outlet check 47a in a passage, partly shown at 48 communicating with any suitable point in the carburetor barrel.

A torsion spring 50 is wound about pump lever shaft 35 and has one end 51 hooked over the portion 34 of the pump leverage and has a second, longer arm 52 which, in Fig. 1, is hooked over the top of suction piston rod 25. Pump lever 37 is provided with a transverse slot 53 in which there is adjustably positioned a pin 54. Projecting from suction piston rod 25 above pin 54 is a finger 55 forming, in effect, a one-way operative connection between the pump leverage and the metering pin control mechanism.

Rod 25 operates in a guiding boss 56 projecting above bowl cover 36 and on one side of this projection there is provided a shoulder 57. This shoulder is positioned so as to receive long end 52 of torsion spring 50 when it is disconnected from suction piston rod 25. (Figs. 2 and 3.)

As best shown in Fig. 5, pin 54 is partially threaded and is releasably attached in position in slot 53 by means of a nut 60 and lock washer 61 so that the pin may be secured either above or

below finger 55 projecting from piston rod 25 or may be entirely removed so as to free the suction metering mechanism from the influence of the pump leverage.

- 5 The operation of the mechanism is as follows: Torsion spring 50 is stronger than spring 21 tending to elevate suction piston 20 so that when extension 52 on the torsion spring is hooked over piston rod 25, finger 55 on the piston rod held
- 10 permanently in engagement with pin 54, as shown in Fig. 1. In this position of the parts, the metering rod is fully responsive to movement of the throttle and the suction control is eliminated. This type of metering control is particularly advantageous with a Chevrolet engine, for instance, when used without a governor.
- 15 Fig. 2 shows torsion spring extension 52 hooked over shoulder 57 on piston rod guiding boss 56 so as to substantially continue the effect of this spring upon the resiliency of the pump operating leverage. Pin 54 is removed from slot 53 so that the manual control of the metering pin is eliminated entirely. In this figure, the metering mechanism becomes fully automatic or suction controlled in accordance with differential pressures exerted upon piston 20 through atmospheric port 18 and suction passage 19 in opposition to spring 21. This arrangement is particularly advantageous with an engine such as that used in the Plymouth automobile since with this type of engine added enrichment should be provided in accordance with manifold suction when the throttle is in a partially open position and the engine subjected to an increased loading. Where
- 20 a governor is used, as stated above, it is desirable that the metering pin be drawn downwardly to a restricting position in the metering orifice as soon as the governed speed is reached during acceleration and held in this position thereafter even though the throttle may be fully opened or nearly so. The full suction controlled metering in Fig. 3 satisfies both requirements.
- 25
- 30
- 35
- 40
- 45
- 50
- 55

In the third arrangement shown in Fig. 3, pin 54 is located in slot 53 above finger 55 on suction piston rod 25 and torsion spring extension 52 is hooked over shoulder 57 and released from rod 25, as in Fig. 2. This provides for a limitation of the upward movement of metering mechanism under the influence of spring 21, in accordance with the position of the pump leverage and throttle valve, while permitting lowering of the metering pin to a restricting or economy position when justified by relatively high intake suction, regardless of the position of the throttle valve. This arrangement is beneficial when used with an engine such as the Chevrolet having a governor applied thereto.

Obviously, the adjustments and modifications above described may be easily made in the field so that a single carburetor may be made to function satisfactorily for a number of different applications. Thus, a garageman or retail merchant need stock a much smaller number of carburetors as a single carburetor may be readily adjusted to function properly with or without governor and with different types of engines. Ordinarily, the mere changing of metering orifices and metering rods is not enough to adapt a carburetor for the varied usages mentioned above, including satisfactory performance either in connection with the governor or without one.

Various features may be modified as will occur to those skilled in the art and the exclusive use of all such modifications as come within the scope of the appended claims is contemplated.

I claim:

1. In a carburetor, an induction conduit, a throttle therein, a metering pin, means to control said pin responsive to suction conditions in said conduit, a throttle actuated member, and cooperating elements normally movable with said pin and said member to provide for one way operation of said pin by said throttle, one of said cooperating elements being capable of predetermined selective assembly with relation to the other cooperating element whereby the desired direction of movement of the pin by throttle movement may be obtained.

2. A carburetor as specified in claim 1 further including a device carried by the carburetor and selectively movable to a first position to maintain said cooperating elements constantly in engagement for full throttle control of said metering pin and to a second position to release said elements.

3. In a carburetor, a mixture conduit, a throttle therein, an accelerating pump, a resilient operative connection between said throttle and said pump, mechanism including a metering pin and a device responsive to suction conditions in said conduit for controlling said pin, cooperating elements on said resilient connection and said pin forming a one-way operative connection between said throttle and said pin, a normally stressed spring applied to one end to said connection and affecting the resiliency thereof, and holding catches on said metering pin mechanism and adjacent the same, the other end of said spring being normally applied to one of said catches and being selectively movable therebetween without substantially varying the effect of said spring upon said connection.

4. In a carburetor, an induction conduit, a throttle therein, an accelerating pump, an operative connection between said throttle and said pump including pivoted levers having cooperating abutments forming a one-way connection therebetween, spring means normally stressed to urge said abutments into engagement, suction controlled metering pin mechanism, cooperating elements on one of said pump levers and said mech-

anism forming a one-way operative connection therebetween, and catch abutments on said mechanism and adjacent the same, said lever spring means having a projection selectively engageable with one or the other of said catch abutments without substantially affecting the stressing of said means.

5. A carburetor as specified in claim 4 in which said metering pin mechanism includes yielding means normally urging said mechanism in opposition to the suction effect thereon, said spring projection, when engaged with the catch abutment on said metering pin mechanism affecting the actuation of said mechanism by said yielding means.

6. In a carburetor, an induction conduit, a throttle therein, a member movable with said throttle, a metering pin, operating mechanism for said pin including cooperating elements normally connected respectively with said pin and said member whereby said elements constitute a one-way control for said mechanism, and means responsive to suction changes in said conduit for supplying actuating force to said mechanism during operation of the carburetor, one of said cooperating elements being removable to eliminate the controlling effect of said actuator upon said metering mechanism, and being further capable of selective assembling with respect to the other element to provide a one-way control of said metering pin in either direction.

7. In a carburetor for an internal combustion engine, a throttle, a fuel metering orifice and metering valve therefor, means responsive to engine suction for operating said valve, a throttle actuated member having a slot, said suction responsive means having an element adjacent said slot, and a valve actuator secured in said slot and forming with said element a one-way operative connection between said throttle actuated member and said valve, said actuator being selectively adjustable in said slot to positions on either side of said actuator for reversing the effectiveness of said one-way connection.
